Application January 10, 1945, Serial No. 572,178

15 Claims. (Cl. 244—14)

1

This invention relates to attack against a moving enemy from a base by means of a ray-guided missile.

An object is to provide a method of control whereby a missile is guided toward collision with an enemy craft all during the time after it has left the launching station until it explodes near the enemy craft.

Another object is to provide a self-steering submarine torpedo which shall travel in pre-determined relation to rays emitted from a target, till detonation occurs.

Our invention is particularly concerned with a missile or projectile capable of changing its own course after launching which no ordinary projectile can do, it being well understood that if a target changes course or speed after an ordinary projectile, aimed to hit it has left its gun, a miss is sure to be registered.

The plan is to "illuminate" the target, preferably by means of a radar transmitter, then to launch the missile or torpedo and guide it by rays reflected back from the target. Our new guided projectile or missile is launched into the air (or water), picks up these rays and guiding itself upon them, chooses a course which will bring it closer and closer to the target. In this way a target will be hit, no matter what evasive tactics it employs.

We are well aware that to guide a missile to a target along rays therefrom has been proposed, but such methods cause the missile, to be launched in the general direction of the target, and then propose to have it swing around a curve and "chase" the target until it is hit. Or the missile is kept in the line of sight to the target by rays reaching it directly from the tracking radar. In this connection we have found, that, for straight flight these methods are fairly feasible, but if a target undertakes evasive action, the rapid turns necessary to the missile, cause centrifugal forces within it of magnitudes too great for practical design. Our calculations have shown such forces to reach a maximum of even 100 G, under extreme conditions.

However, in the methods which we propose, no very great centrifugal forces are encountered, since the projectile travels, once it has oriented itself after launching, for the most part fairly straight so long as the target flies straight, and does not change speed. Our novel missile, shortly after launching, chooses, preferably, a collision course to the target while its ray-guided control faces in a different direction, that is, towards the target. The preferred method, car-

2

ried out automatically by the apparatus of our invention, it will be seen, is the method which could be used by a swimmer bearing a hand grenade in an attack on a moving boat, for instance. Such a swimmer, according to our new method, would launch himself into the water towards the then position of the boat, keep his eyes on the same while swinging his body around towards parallelism with its motion and at the same time pivoting his head on his body in opposite sense to the swinging of his body in order to keep in view the boat. Eventually, the swimmer having more speed than the boat, the head, with eyes fixed on the target, would cease to turn further on the body and the body cease to change course because the swimmer, by so maneuvering, would have gotten his body on collision course to the boat, meeting it after an interval determined by the excess of speed the swimmer has over the boat, as is well understood.

For a more complete understanding of the invention, reference may be had to the accompanying drawings, in which:

Figure 1 is a schematic diagram illustrating the general mode of operation of the missile guiding apparatus of this invention, prior to flight of the missile;

Fig. 2 is a similar diagram, illustrating conditions during flight of the missile toward the target;

Fig. 3 is a perspective view of the guided missile of this invention, certain portions being shown exposed with the casing broken away in the interest of clarity;

Fig. 3a illustrates a modified form of the gyroscope control system of Fig. 3;

Fig. 4 is a perspective view of the missile of this invention, including the housing which is incompletely shown in Fig. 3;

Fig. 5 is a perspective view of a wing-borne modification of the missile of this invention, the housing being broken away to show the interior construction; and

Fig. 6 illustrates diagrammatically an electro-mechanical induction resolver utilized for introducing corrections into the steering mechanism of the missile shown in Fig. 5.

Referring to Fig. 1 of the drawings, numeral 10 designates a conventional radar or other ray transmitter, which keeps track of, and projects waves against, a moving target, for instance an airplane as illustrated at 11. Of the whole bundle of rays emitted by the transmitter 10, the emitted ray 12 is shown as reflecting back from the target along the line 13 and into the

"dish" or collector 14 and there concentrated upon the ray-receiving antenna mounted therein. This "dish" is universally mounted upon the missile body 15. The whole assembly is shown, ready for launching on the catapult 16 which is about to launch it in the general direction of the predicted impact or collision point 17 for the target direction shown. The dish 14 is, of course, lined up with the ray 13 and forms an angle D with the intended flight path 18 of the missile 15 which carries it. This angle D may be called "deflection" and it is obviously also relative bearing of target measured from the nose of the missile. If the angle D is the correct angle of travel for the missile 15 to hit the target 11 at the point 17, then the line 18 is the collision course for that target. For such a course, it is well-known, that the target bearing angle D remains constant so long as the target maintains its speed and direction and the missile does likewise. In other words, when the target has travelled to the point 19, in its path, the missile will have travelled to the point 20, the then line of (future) guiding rays 19-20 will be parallel to the line of present guiding rays 13 and the then (future) target bearing angle, D₁, will be equal to D, the present target bearing angle, or launching deflection angle. Thus our novel ray-guided missile may be launched with appropriate deflection angle to the radar rays reflected from a target and travel to collision with the target by keeping this angle constant.

Now, we realize, that such a launching procedure is in common use in firing an ordinary projectile at a moving target, but with such a projectile there is no guidance for the missile after it leaves the gun, whereas our novel missile is guided during the whole time of its travel. Furthermore, in gun fire, should a target change course or speed after the angle D was calculated, the target would not be hit, whereas our novel projectile will hit in spite of any evasive action of the target.

For instance, referring again to Fig. 1, should the target 11, at the point 19 start to veer as shown in the drawing our novel missile, by the peculiar action of the apparatus, to be described, would change course accordingly and select a new deflection angle D₂, then a second new angle D₃ and then maintain the latter constant because the target has ceased to veer and pursues another straight path 21, as shown.

Although this plan is perfectly feasible, there is, however, a better plan preferred by us, at the present time. Some time is necessarily required to calculate the angle D and in modern warfare time is at a premium. For this reason we have invented our preferred system which obviates this difficulty quite completely. Our method permits the missile to be launched directly at the target, if desired, and allowed to find its own deflection or relative target bearing angle D, and the appropriate collision course. This action occurs, as hereinafter described in detail, because of the articulation of the ray-sensitive dish 14 upon the missile body 15 and the cross-connected servo-mechanisms shown in the figures.

How this is accomplished we have illustrated in the diagram of Fig. 2, to which reference is now taken.

In this illustration the missile 15 is shown in flight in correct orientation to hit the target 11 at the point 17 and the target has flown from the point 22 at which the missile was discharged

from the catapult 16, which is shown as still aiming at that point. The missile has steered itself around the curve 23 to the position in which it is shown and is now being guided towards collision with the target by the reflected ray 13 from the radar transmitter 10 received into the dish 14. By using this method, without calculating deflection, the missile may be discharged at the target and, if its speed at first is not up to maximum or changes in flight no harm will be done, whereas, in the method of Fig. 1 a value of speed has to be assumed both for target and missile in order to calculate the angle D.

In both the methods described above, guidance of the missile on collision course to the target is obtained by keeping the angle of relative target bearing D, as nearly constant as possible. To say this is to define again the phrase "collision course" which is understood in navigation to be that course of one ship toward another moving ship characterized by the fact that the angle, between the bow of the first-mentioned ship and a line of sight to the moving ship, remains constant. The angle D is kept constant by the missile changing course to keep the dish 14 aligned with the rays reflecting from the target. A refinement of this plan which we have incorporated in our invention is to keep constant the true target bearing angle of target to missile rather than the relative target bearing angle of target to missile. This insures that the direction of the dish 14 will be more stable and not caused to oscillate across the guiding rays due to the correcting maneuvers of the missile, itself. We accomplish this by incorporating gyroscopes as will hereinafter be described. By true bearing, of course, we mean the bearing of the dish 14 to the meridian.

Referring now to Fig. 3 we will describe, in detail, the mechanism, which we at present prefer, to accomplish our novel results. Here the missile is again designated 15 (but has parts broken away to show interior mechanism) and the ray-receiving dish 14. The dish is universally mounted at the front of the device and the propelling and steering rocket is shown at 24. A weight 25 attached to the underside of the missile acts as a guide in launching in cooperation with the slot in the catapult 16, and also to keep the missile upright in its flight. Explosive may be carried in the compartment 26.

In Fig. 3 the dish at 14 has shown, within it, in dotted lines, the antennae 27, 28. The antenna 27 is provided to detect deviation of the received rays laterally and the antenna 28 is provided to detect deviation of the received rays vertically. The antenna indicated in the drawings at 27 and 28, being no part of our invention, may be of any type of device known to be sensitive to the angle of impingement of rays upon the reflector-dish 14 and may conveniently be of the type shown in the United States patent to Henri Moueix, Serial No. 2,176,469 patented October 17, 1939. In this case the transmitted rays from our transmitter shown at 10, Figs. 1 and 2, would be duplex, as described by the inventor, with differentiating modifications, and in both the vertical and the horizontal. The dish or reflector 14 containing the antennae is universally mounted as shown, having one axis disposed for lateral alignment of the dish and another axis for vertical alignment of the same as shown, the dish 14 being fixedly mounted on the element or bail 29, which is pivoted top and bottom in the ring or bail 30. This bail is itself

mounted in bearings in the struts 31 for rotation in the vertical plane and thus the well-known Cardan, Hooke's or universal joint is provided for the dish 14 with its antennae 27, 28. Upon the thus universally mounted dish-carrying element 29 are carried also two rate gyroscopes, that shown at 32 being provided for lateral rate and that shown at 33 for vertical rate. In order that these controlling gyroscopes may control the dish 14 follow-up motors are provided, that at 34 being provided for lateral control and that at 35 for vertical control. The gyroscope 32 is provided with a magnet 36 which cooperates with the follow-up coil 37 mounted on the element 29 to control the motor 34 (through suitable power amplifier 38 which may be like that shown in Sect. 7—page 84 of Electrical Engineer's Hand Book by Pender & McIlwain, vol. 5). The vertical rate gyroscope 33 is provided with a magnet 39 which cooperates with the follow-up coil 40 to control the motor 35 (also through another similar power amplifier 41). Any deviation of the dish 14 laterally, due to swinging of the missile in space, will cause the gyroscope 32 to precess against the spring 42, actuate the follow-up coil 37 and the motor 34 to swing the element 29 in the ring, 30, and any deviation vertically, due to swinging of the missile in space, will act likewise to swing the bail 30 in the vertical, both these corrections being relative to the missile itself. In this way the dish is caused, as will hereinafter be explained, to maintain alignment with the arriving, guiding waves.

As indicated in Fig. 3, the missile is to be driven preferably by a mechanism of the rocket type shown at 24 mounted by means of its ball portion 43, movably seated in a socket in the rear wall 44 of the missile 15, for universal rotation therein. This rocket is intended to propel the missile and also to steer it under the influence of the received rays impinging on the antenna in the dish or reflector 14. The ball 43 has a tail or steering extension 45 within the missile 15 which is provided with a gear sector 46 to which is geared a motor 47. This motor is mounted on a bail 48 which is pivoted as shown in the back wall 44, concentric with the ball 43 and in a plane at right angles to the keel weight 25. A second motor 49 mounted within the missile, through the sector 50, is adapted to swing the bail 48 in the vertical. By these means the rocket may be aimed in any direction relative to the missile and thus steer it as required. When no current is fed to the motors 47 and 49 the centering springs 53 shown restore the rocket 24 to alignment with the axis of the missile as is well understood. Power may be supplied by multiple storage battery shown at 86. The dotted lines represent electrical connecting cables.

The operation of the device just described and shown in Fig. 3 is as follows:

The missile, with its equipment, is launched, preferably, towards the target, with the dish 14 as shown lined up with the arriving rays and the axis of the missile 15, as is also the rocket 24. The gyroscopes are spinning and the dish 14 is concentrating the rays being received from the target on to the antennae 27 and 28. The missile is speeding towards the initial position of the target, toward which it was launched, and the arriving rays entering the dish 14 are beginning to deviate from the centerline of the dish in the direction of flight of the target. The antennae 27, 28 perceive the deviation, analyze it (after the manner of Moueix, above-mentioned, for in-

stance) and feed impulses, through the power amplifiers 51 and 52 (similar to the one marked 38) to the steering motors 47 and 49. This causes the missile to steer around in the direction of target flight carrying with it the dish 14 with its gyroscopes 32 and 33. The gyros feel immediately the angular change and precess accordingly, causing the follow-up motors 34 and 35 to swing the dish 14 upon the missile 15, by deliberate cross-connection of wiring, in the opposite direction to the target motion. This opposite swing of the dish 14 across the guiding rays, momentarily aggravates the deviation and causes the steering motors 47 and 49 to swing the missile around in direction of target flight at a rate much greater than the ray deviation rate. Of course, all these motions occur practically simultaneously, and the net result is that the dish 14 follows the guiding rays, and the missile steers rapidly around in direction towards collision course. (Such a course, it will be recalled, is a course for the missile 15, such that the dish 14 is kept facing the target, with only momentary drift therefrom.) When the antennae 27, 28 detect no more deviation the missile is on collision course and dish and missile remain disposed at an angle, as is illustrated in both Figures 1 and 2.

The previously proposed "chasing" types of guided missile are quite different from our type of guided missile in that with them, when the guiding ray swings around, the missile swings in the same direction at the same speed and the dish and missile are always lined up with each other. In our type, however, the missile is no sooner launched at the target, than the dish and missile start getting out of line, only stopping the process when collision course is found. Our missile flies along in one direction with the dish looking in another entirely different direction.

In Fig. 3, it will be understood that for the purpose of clarity, we have shown the gyro system out in the air in front of the missile body but it will be recognized that such an arrangement is only theoretical. Actually all the mechanism is snugly housed in the body of the missile and such a practical form of our invention may take the shape shown in Fig. 4. This figure is, we believe, self-explanatory, like parts being like numbered, as in the other figures.

In Fig. 5 a more elaborate form of our invention is shown. The missile in this form has airfoils, rudder and elevator, wings and ailerons in order to be able to make sharper turns. The dish, antenna and its mountings are shown quite the same as in the other figures and are like numbered, but a third gyroscope is provided to stabilize the system in the horizontal when the missile is banking. In other words, our missile here takes the form more of a "robot" attack plane than of a simple projectile.

Referring now to Fig. 5 the device will be described in detail.

The antenna dish 14 is mounted as before on the element 29 which, in turn, is carried by the ring 30, pivoted in the member 31. Gyros are provided for lateral and vertical correction and all parts cooperating therewith are quite similar to those shown in Fig. 3 being also numbered likewise. The member 31, which was, in Fig. 3, a pair of supporting struts extending from the missile body, has become, in Fig. 5, a fork or yoke and instead of being fixedly mounted on the missile body 15, it is here pivoted in the missile body, as shown, for axial rotation therein being

carried in the journals 54 and 55. By this means the dish 14 is given a third axis of adjustment which renders it mechanically independent of the angular maneuvers of the missile body 15. The reason for this third pivot will be clear when it is realized that a missile, with wings such as this one has, must bank in order to make turns and such banking would disturb the gyros 32 and 33. But, for this very reason, another gyro and associated control must be provided to control this pivot and keep the supporting axis of the ring 30 in the fork 31 at all times substantially horizontal. This additional gyroscope is indicated at 56 in Fig. 5 and has, as do the other gyros, a follow-up coil 57, a cooperating gyro magnet 58, a restraining spring 59 and follow-up motor 60. When banking, or other motion of the missile body, tends to force the axis of the ring 30 out of the horizontal, the gyro 56, by the means above-described, causes the follow-up motor 60 to change the angular relation of the fork 31 to the missile body 15 to make the necessary correction. By the use of three gyroscopes and their associated apparatus in this manner the dish 14 tends to maintain, at all times, its orientation in space, as explained in detail in connection with the description of Fig. 3.

In the Fig. 5 under consideration, the steerable rocket shown in Fig. 3 is replaced by a fixed rocket 61, and conventional aircraft rudder 62, elevator 63 and ailerons 64. The rudder 62 is controlled as in Fig. 3 by the follow-up motor 65 operated thru the power amplifier 66 and the elevator 63 is controlled by the follow-up motor 67 through the amplifier 68, both being primarily controlled by the antenna in the dish 14 thru the cables indicated as dotted lines. The ailerons are caused to keep the plane of the wings of the missile perpendicular to the resultant of gravity and centrifugal force, as is well understood, by means of a simple pendulum P and contacts 69 and motor 70 driven by amplifier 72. Thus, when the operation of the rudder causes the missile to turn and the pendulum P to swing, the ailerons 64 cause the device to bank properly. The banking action, however, causes the plane of the wings to make (in rapid turns in following evasive targets) quite an angle with the plane of the controlling member, but the system supporting the dish 14 remains on even keel, due to the gyro 56, and therefore the signals from the same are reproduced on the rudder and elevator distorted by the trigonometric functions of the said angular displacement. In extreme cases, where the missile banks almost to the vertical, deviation of the guiding rays in the horizontal plane would be causing correction by rudder in almost a vertical plane with practical loss of control of the missile. For this reason we have provided a correcting resolver at 71 which we prefer, at the present time, to be an electrical resolver of the well-known synchronous motor type, such as is described in Patent No. 2,467,646, for example. This displacement or banking angle, as measured by gyro 56, is fed mechanically into the resolver 71 and the signals corrected by the necessary trigonometric functions. The resolver 71 is actually a pair of resolvers made in one unit, one for elevation and the other for steering. The windings are diagrammatically shown in the small Fig. 6. In this figure, the body of the resolver is indicated by the dotted line 73, the rotor bearing shaft 74 (shown also in Fig. 5). The rotor (not shown) carries the windings 75

and 76 and the shell or stator 73 carries the windings 76 and 77. When in the position shown the coils on the stator repeat signals to the coils on the rotor in one to one ratio corresponding to the condition when the craft is on even keel (not banked). But when the shaft 74 is rotated by the gyro follow-up motor 60 the coils of stator and rotor are thrown out of line and the signals produced in the rotor are trigonometric functions of those in the stator. The input leads 78 for the stator coil 76 are represented, in Fig. 5, by the dotted cable 79 and the output or rotor leads 80 are represented in Fig. 5 by the dotted cable 81. This completes the rudder correction and the elevator system is as follows—stator coil leads 82 correspond to the dotted cable 83 and the rotor or output leads 84 correspond to the dotted cable 85 in Fig. 5. The missile of Fig. 5 just described is launched similarly to that of Fig. 3 and keeps its radar ray receiver dish 14 lined up with the guiding rays while the winged missile body finds the collision course to the ray reflecting target. But, due to its airplane type controls, this form of our invention is better adapted to attack rapidly maneuvering targets, such as dive bombers or destroyers.

While we have illustrated in Figs. 3 and 5 various forms of our invention, the forms shown have one thing in common, the fact, that in operation the initial deviation of the guiding ray causes the missile proper to swing rapidly in the same direction, which motion causes the gyro systems to swing the dish in the opposite direction on the missile. However, we have considered another method of electrical connection of the same elements of our invention, in which the deviation of the guiding rays causes the dish and gyros to be swung (by the motors 34 and 35) in the opposite direction on the missile (after a momentary forward motion) and the missile immediately thereafter to be swung in the same direction as the deviation. This form is easily made from the form shown in Fig. 3 by switch electrical cables as shown in Fig. 3a, wherein all parts are similar to those of Fig. 3 and like-numbered. However, this form of our invention has the same basic feature as the other forms shown, that is the swinging of the ray-receptor on the missile in opposite sense to the ray deviation and the missile in the same sense but faster.

Although we have confined our description of our invention to combat in the air, we do not limit ourselves to this use, but propose to control submarine torpedoes by sound waves also. Besides these we plan power attack missile boats and "tanks" for land use.

Of course, it will be obvious that many other forms of our invention could be developed working on the same principle, and therefore we do not wish to limit ourselves to the forms described above, but rather to have the scope of the invention defined by the appended claims.

We claim:

1. In a ray-guided, explosive missile having a duo-planar ray-receptor and a duo-planar steering mechanism, the combination therewith of gimbals for mounting said receptor, a pair of gyroscopes severally connected to said gimbals, means restraining one of said gyroscopes to one degree of freedom in one plane, means restraining the other gyroscope to one degree of freedom in another plane, follow-up motors for said gyroscopes operatively connected to the corresponding gimbals, and operative connections from said ray-receptor to said steering mechanism where-

by said missile is adapted to receive guiding rays while travelling on a straight course at an angle to said rays.

2. In a ray-guided, explosive missile having a duo-planar ray-receptor and a duo-planar steering mechanism the combination therewith of gimbals for mounting said receptor, a pair of gyroscopes severally connected to said gimbals, means restraining one of said gyroscopes to one degree of freedom in one plane, means restraining the other gyroscope to one degree of freedom in another plane, follow-up motors for said gyroscopes operatively connected to the corresponding operative connections from receptor to said gimbal motors, whereby said missile is adapted to receive guiding rays while travelling on a straight course at an angle to said rays.

3. In a ray-guided explosive vehicle adapted to be directed to a remote target, the combination of a support, steering mechanism therefor, a ray receptor, a universal joint including a gimbal mounting said receptor on said support, means responsive to deviation of the impingement angle on said receptor of rays reflected from the target, a gyroscope carried by said gimbal and having a single suspension axis for movement in one plane, means restraining the said movement of said gyroscope in said one plane, a second gyroscope carried by said gimbal and having a single suspension axis for movement in another plane, means restraining the said movement of said second gyroscope in said other plane, follow-up mechanism responsive to relative movements of said gyroscopes in the said respective planes, motive means operatively connected to said gimbal for driving the same, motive means operatively connected to said steering mechanism for driving the same, and means jointly controlled by said gyroscope follow-up mechanism and said ray-responsive means for severally energizing said motive means to maintain constant the said angle of ray impingement on said receptor.

4. In a ray-guided explosive vehicle adapted to be directed to a remote target, the combination of a support, steering mechanism therefor, a ray receptor universally mounted on said support, means responsive to deviation of the impingement angle on said receptor of rays reflected from the target, motive means energized by said responsive means, operative connections between said motive means and said steering mechanism, a gyroscope responsive to change of course of said vehicle in one plane, a second gyroscope responsive to change of course of said vehicle in another plane, follow-up mechanism severally actuated by the response of said gyroscopes, motive means energized by said follow-up mechanisms, and operative connections between said last-named motive means and said ray receptor for driving the latter to restore the impingement angle of said rays thereon.

5. In a ray-guided explosive vehicle adapted to be directed to a remote target, the combination of a support, steering mechanism therefor, a ray receptor universally mounted on said support, means responsive to deviation of the impingement angle on said receptor of rays reflected from the target, motive means energized by said responsive means, operative connections between said motive means and said steering mechanism, a gyroscope responsive to change of course of said vehicle in one plane, means restraining the response of said gyroscope, a second gyroscope responsive to change of course of

said vehicle in another plane, means restraining the response of said second gyroscope, follow-up mechanism severally actuated by the response of said gyroscopes, motive means energized by said follow-up mechanisms, and operative connections between said last-named motive means and said ray receptor for driving the latter to restore the impingement angle of said rays thereon.

6. In a ray-guided explosive vehicle adapted to be directed to a remote target, the combination of a support, steering mechanism therefor, a ray receptor universally mounted on said support, means responsive to deviation of the impingement angle on said receptor of rays reflected from the target, motive means energized by said responsive means, operative connections between said motive means and said steering mechanism, a gyroscope operatively connected to said receptor and responsive to change of course of said vehicle in one plane, a second gyroscope operatively connected to said receptor and responsive to change of course of said vehicle in another plane, follow-up mechanism severally actuated by the response of said gyroscopes, motive means energized by said follow-up mechanisms, and operative connections between said last-named motive means and said ray receptor for driving the latter to restore the impingement angle of said rays thereon.

7. In a ray-guided explosive vehicle adapted to be directed to a remote target, the combination of a support, steering mechanism therefor, a ray receptor, a gimbal suspension for said receptor on said support, means responsive to deviation of the impingement angle on said receptor of rays reflected from the target, motive means energized by said responsive means, operative connections between said motive means and said steering mechanism, a gyroscope carried by one of said gimbal and responsive to change of course of said vehicle in one plane, a second gyroscope carried by said gimbal and responsive to change of course of said vehicle in another plane, follow-up mechanism severally actuated by the response of said gyroscopes, motive means energized by said follow-up mechanisms, and operative connections between said last-named motive means and said ray receptor for driving the latter to restore the impingement angle of said rays thereon.

8. In a ray-guided explosive vehicle adapted to be directed to a remote target, the combination of a support, steering mechanism therefor, a ray receptor universally mounted on said support, means responsive to deviation of the impingement angle on said receptor of rays reflected from the target, motive means energized by said responsive means, operative connections between said motive means and said receptor for driving the latter to restore the impingement angle of said rays thereon, a gyroscope responsive to movement of said receptor in one plane, a second gyroscope responsive to movement of said receptor in another plane, follow-up mechanisms severally actuated by the response of said gyroscopes, motive means energized by said follow-up mechanisms, and operative connections between said last-named motive means and said steering mechanism for changing the course of said vehicle.

9. In a ray-guided explosive vehicle adapted to be directed to a remote target, the combination of a support, steering mechanism therefor, a ray receptor universally mounted on said support, means responsive to deviation of the im-

11

pingement angle on said receptor of rays reflected from the target, motive means energized by said responsive means, operative connections between said motive means and said receptor for driving the latter to restore the impingement angle of said rays thereon, a gyroscope responsive to movement of said receptor in one plane, resilient means restraining the response of said gyroscope, a second gyroscope responsive to movement of said receptor in another plane, resilient means restraining the response of said second gyroscope, follow-up mechanism severally actuated by the response of said gyroscopes, motive means energized by said follow-up mechanisms, and operative connections between said last-named motive means and said steering mechanism for changing the course of said vehicle.

10. In a ray-guided explosive vehicle adapted to be directed to a remote target, the combination of a support, steering mechanism therefor, a ray receptor universally mounted on said support, means responsive to deviation of the impingement angle on said receptor of rays reflected from the target, motive means energized by said responsive means, operative connections between said motive means and said receptor for driving the latter to restore the impingement angle of said rays thereon, a gyroscope connected to said receptor and responsive to movement of said receptor in one plane, a second gyroscope connected to said receptor and responsive to movement of said receptor in another plane, follow-up mechanisms severally actuated by the response of said gyroscopes, motive means energized by said follow-up mechanisms, and operative connections between said last-named motive means and said steering mechanism for changing the course of said vehicle.

11. In a ray-guided explosive vehicle adapted to be directed to a remote target, the combination of a support, steering mechanism therefor, a ray receptor, a gimbal suspension for said receptor on said support, means responsive to deviation of the impingement angle on said receptor of rays reflected from the target, motive means energized by said responsive means, operative connections between said motive means and said receptor for driving the latter to restore the impingement angle of said rays thereon, a gyroscope carried by one of said gimbal and responsive to movement of said receptor in one plane, a second gyroscope carried by said gimbal and responsive to movement of said receptor in another plane, follow-up mechanisms severally actuated by the response of said gyroscopes, motive means energized by said follow-up mechanisms, and operative connections between said last-named motive means and said steering mechanism for changing the course of said vehicle.

12. In a ray-guided explosive vehicle adapted to be directed to a remote target, the combination of a support, steering mechanism therefor, a ray receptor, a universal joint including a gimbal mounting said receptor on said support, means responsive to deviation of the impingement angle on said receptor of rays reflected from the target, a gyroscope carried by said gimbal and having a single suspension axis for movement in one plane, means restraining the said movement of said gyroscope in said one plane, a second gyroscope carried by said gimbal and having a single suspension axis for movement in another plane, means restraining the

12

said movement of said second gyroscope in said other plane, follow-up mechanism responsive to relative movement of said gyroscopes in the said respective planes, motive means operatively connected to said gimbal for driving the same, motive means operatively connected to said steering mechanism for driving the same, means jointly controlled by said gyroscope follow-up mechanism and said ray-responsive means for severally energizing said motive means to maintain constant the said angle of ray impingement on said receptor, and stable means on said support connected to said gimbal for stabilizing the same.

15. 13. In a ray-guided explosive vehicle adapted to be directed to a remote target, the combination of a support, steering mechanism therefor, a ray receptor, a universal joint including a gimbal mounting said receptor on said support, means responsive to deviation of the impingement angle on said receptor of rays reflected from the target, a gyroscope carried by said gimbal and having a single suspension axis for movement in one plane, means restraining the 20 said movement of said gyroscope in said one plane, a second gyroscope carried by said gimbal and having a single suspension axis for movement in another plane, means restraining the said movement of said second gyroscope in said 25 other plane, follow-up mechanism responsive to relative movement of said gyroscopes in the said respective planes, motive means operatively connected to said gimbal for driving the same, motive means operatively connected to said steering mechanism for driving the same, means jointly controlled by said gyroscope follow-up 30 mechanism and said ray responsive means for severally energizing said motive means to maintain constant the said angle of ray impingement on said receptor, a third gyroscope mounted on said support and responsive to unstable movements thereof, follow-up mechanism responsive to relative movement of said third gyroscope, third motive means energized thereby, and operative 35 connections between said third motive means and said gimbal for stabilizing said receptor.

14. In a ray-guided explosive vehicle adapted to be directed to a remote target, the combination of a support, steering mechanism therefor, a ray receptor, a universal joint including a gimbal mounting said receptor on said support, means responsive to deviation of the impingement angle on said receptor of rays reflected from the target, a gyroscope carried by said gimbal and having a single suspension axis for movement in one plane, means restraining the said movement of said gyroscope in said one plane, a second gyroscope carried by said gimbal 50 and having a single suspension axis for movement in another plane, means restraining the said movement of said second gyroscope in said other plane, follow-up mechanism responsive to relative movement of said gyroscopes in the said 55 respective planes, motive means operatively connected to said gimbal for driving the same, motive means operatively connected to said steering mechanism for driving the same, means jointly controlled by said gyroscope follow-up mechanism and said ray-responsive means for severally energizing said motive means to maintain constant the said angle of ray impingement on said receptor, a third gyroscope mounted on said support and responsive to unstable movement thereof, a transformer having its energized 60

75

stator winding fixed to said support and its rotor winding pivoted about the fore-and-aft axis, operative connections between said third gyroscope and said rotor winding for relatively rotating the same about said axis to induce a corresponding voltage therein, and electrical connections between the output of said rotor winding and the steering mechanism motive means for modifying the operation thereof in accordance with the unstable movements of said support in flight.

15. In a ray-guided explosive vehicle adapted to be directed to a remote target, the combination of a support, steering mechanism therefor, a ray receptor, a universal joint including a gimbal mounting said receptor on said support, means responsive to deviation of the impingement angle on said receptor of rays reflected from the target, a gyroscope carried by said gimbal and having a single suspension axis for movement in one plane, means restraining the said movement of said gyroscope in said one plane, a second gyroscope carried by said gimbal and having a single suspension axis for movement in another plane, means restraining the said movement of said second gyroscope in said other plane, follow-up mechanism responsive to relative movement of said gyroscopes in the said respective planes, motive means operatively connected to said gimbal for driving the same, motive means operatively connected to said steering mechanism for driving the same, means jointly controlled by said gyroscope follow-up mechanism and said ray-responsive means for severally energizing said motive means to maintain constant the said angle of ray impingement on said receptor, a third gyroscope mounted on said support and responsive to unstable movement thereof, follow-up mechanism responsive to relative movement of said third gyroscope

Certificate of Correction

Patent No. 2,557,401

June 19, 1951

GEORGE AGINS ET AL.

It is hereby certified that error appears in the printed specification of the above numbered patent requiring correction as follows:

Column 9, line 14, before the word "operative" insert *steering mechanism, motors geared to said gimbals and;*

and that the said Letters Patent should be read as corrected above, so that the same may conform to the record of the case in the Patent Office.

Signed and sealed this 4th day of September, A. D. 1951.

[~~SEAL~~]

THOMAS F. MURPHY,
Assistant Commissioner of Patents.
